[57] CLAIM

The ornamental design for a base for a telephone set, substantially as shown and described.

DESCRIPTION

FIG. 1 is a front, top and right side perspective view of a base for a telephone set showing my new design; FIGS. 2 and 3 are respectively top and bottom plan views thereof;

FIGS. 4 and 5 are respectively right and left side elevational views thereof;

FIGS. 6 and 7 are respectively front and rear elevational views thereof;

FIG. 8 is a right side elevational view, showing an alternate mounting position; and

FIG. 9 is a front, top and right side perspective view of a second embodiment thereof, the sole difference being an alternate pushbutton arrangement.

FIG. 1

FIG. 2

FIG. 3

FIG. 4

FIG. 5

FIG. 6

FIG. 7

FIG. 8

FIG. 9
